UNITED STATES PATENT OFFICE

130,582

DESIGN FOR A BUILDING

Gordon B. Kaufmann, Los Angeles, Calif.

Application July 7, 1941, Serial No. 101,931

Term of patent 3½ years

To all whom it may concern:

Be it known that I, Gordon B. Kaufmann, a citizen of the United States of America, residing at Los Angeles, in the county of Los Angeles, State of California, have invented a new, original, and ornamental Design for a Building, of which the following is a specification, reference being had to the accompanying drawing, forming a part thereof.

Fig. 1 is a perspective view showing the rear, top and one end of a building showing my new design, and

Fig. 2 is a perspective view showing the front, bottom and other end of said building.

I claim:

The ornamental design for a building, as shown.

GORDON B. KAUFMANN.
